United States Patent Office

Des. 225,798
Patented Jan. 9, 1973

225,798

BENCH

Frank R. Torrey, 9805 Dallas Ave.,
Silver Spring, Md. 20901

Filed Feb. 19, 1971, Ser. No. 117,211

Term of patent 14 years

Int. Cl. D6—02

U.S. Cl. D6—59

FIG. 1

FIG. 2

FIG. 3

FIG. 1 is a perspective view of a bench, showing my new design;

FIG. 2 is a rear elevational view thereof, and

FIG. 3 is a left side elevational view thereof, the right side being a mirror image thereof.

I claim:

The ornamental design for a bench, as shown and described.
